UNITED STATES PATENT OFFICE.

BENEDICT T. GIBBS, JR., OF CHICAGO, ILLINOIS, ASSIGNOR TO MORDEN FROG & CROSSING WORKS, OF CHICAGO, ILLINOIS, A CORPORATION OF ILLINOIS.

ADJUSTABLE-GUARD-RAIL BRACE-PLATE.

1,376,525.

Specification of Letters Patent.

Patented May 3, 1921.

Application filed March 5, 1920. Serial No. 363,486.

To all whom it may concern:

Be it known that I, BENEDICT T. GIBBS, Jr., a citizen of the United States, residing at Chicago, in the county of Cook and State 5 of Illinois, have invented a certain new and useful Improvement in Adjustable-Guard-Rail Brace-Plates, of which the following is a specification.

This invention relates to the general 10 class of mechanisms frequently designated "guard rail clamps" for so detachably securing a guard rail to a main rail that, as wear takes place, the guard rail may be adjusted to proper position with a minimum expenditure of work and annoyance.

The object of the invention is to provide such a mechanism mounted upon a brace plate which can be substituted for the ordinary guard rail tie plate, thereby saving the 20 expense of that plate, said brace plate carrying with it the adjusting mechanism which, for required strength, is very light in construction, easily and cheaply made, satisfactory in operation and not readily 25 liable to get out of order.

The invention consists in means for carrying out the foregoing and other objects hereafter more fully set forth in the specification and claims.

30 Referring to the drawings in which like numerals denote like parts throughout the several views,

Figure 1 is a plan view of mechanism illustrating this invention in its preferred 35 form, the same being shown operatively applied to the rails.

Fig. 2 is a sectional detail view on the line 2—2, Fig. 1.

Fig. 3 is a sectional view corresponding 40 to Fig. 2 showing a modified construction in which the vertical angularity of one of the wedge faces is changed.

Fig. 4 is another sectional view showing a slight modification, in the bending of the 45 brace plate.

Figs. 5 and 6 are respectively a plan view and a sectional view on the line 6—6, showing a modified structure in which a cast plate is used in place of the bent construction 50 previously shown.

In the preferred form of construction shown in Fig. 1 a plate 10 of bendable material is provided, adapted to be detachably secured on top of the tie 12 by any 55 suitable means, which in the particular case

here illustrated, takes the form of two spikes 14 so placed as to engage in addition the outer flange 16 of the main rail 18, and two other spikes 20 conveniently located near the other end of the plate. 60

The end of the plate 10 which is adjacent to the main rail 18 preferably has some portion turned up over the flange 16 of the rail. In the particular case here illustrated this turned up portion takes the form 65 of the clip 22 made by notching the plate end in the parallel lines 24.

Adjacent to the main rail 18 is placed a guard rail 26 which is to be adjusted in the usual manner, laterally, of the main rail 18. 70 These two rails 18 and 26 are separated by the adjustably spreadable, multiple block mechanism without novelty appearing between them in the drawings. The first block 28 bears against the main rail 18 and 75 is held against longitudinal movement with reference to the rail by downwardly projecting lugs 30 which enter suitable recesses 32 formed for the purpose in the main plate 10. The second block 34 bears against 80 and is slidably lengthwise of the guard rail 26, when it is not held against such movement by the serrated diagonal or wedge face 36, intermeshing with a corresponding face on the block 28. It is entirely apparent 85 from the drawings that by first separating these blocks and moving block 34 upward as viewed in Fig. 1 one serration and then fitting them together again the distance between the flanges of rails 18 and 26 will be 90 lessened and that conversely moving the block downward as viewed in Fig. 1 will increase the total transverse thickness of the combined blocks and thus hold the rails farther than in the previous position. 95

In assembling the two rails either originally or on subsequent adjustment these blocks are interfitted as just described to afford the proper operating distance between the adjacent faces 38 and 40 of the rail heads whereupon the guard rail is moved up against the block combination and secured in place by other mechanism which will now be described.

Having positioned spacing block mechanism 28—34 and moved the guard rail 26 up to place, it is there detachably, adjustably, rigidly secured in place by the mechanism of this invention. This is accomplished by forming on the end of the plate 110

10 which is at the right of the guard rail as shown in Figs. 1 and 2 a bearing block, usually a casting made in the peculiar form shown in the drawings in which there is a 5 central upper portion 44 connecting two vertical, spaced apart, side flanges 42. This center portion 44 has a laterally inclined vertical bearing face 46 above the plate 10 and comparatively near the rail 26, and lower down another vertical but laterally inclined face 48 parallel to the face 46, said latter face 48 being immediately adjacent to the plate 10. This member 42—44 described rises from a base portion comprising two outside flanges 50 secured to the plate 10 by rivets 52, and a central flange portion 54 which is, in the case here illustrated, embraced by an upwardly turned clip 56 cut from the plate 10 and held in place 15 by a rivet 58. This clip is accurately made so that its end 60 abuts against a corresponding face 62 on the central portion 44 of the casting. The result of this construction is that this block is so firmly attached 20 to the plate 10 that it is prepared to resist any horizontal strain created by the movement of the guard rail 26 away from the main rail. Slidably mounted between the guard rail 26 and this block is a wedge block 25 44 adapted to fit under the head of the rail 26 and slide along its web on the straight face 68. The opposite side of this block 64 is provided with angularly inclined wedge faces 70 and 72 engaging respectively the 30 horizontally spaced faces 46 and 48 of the bearing block. Actual experience demonstrates that devices of this kind with a single wedge surface as at 46 only, exert a great bending strain on plate 10 at about 35 the lower portion of rivet 52 which tends to tear the whole mechanism off from the plate and that this trouble is largely, if not entirely eliminated by the use of the two wedge surfaces in different planes. This 40 wedge member 64 is also provided with a horizontal flange 74 traveling in a U-shaped slot 76 in the bearing block, this flange being provided with a series of staggered holes 78 adapted to selectively register with corresponding holes 76 in member 44, a cotter 45 pin 80 being provided for insertion in oppositely disposed holes 76 and 78 to rigidly secure the wedge block 64 in desired selective position.

From the foregoing it will be seen that 55 by properly positioning the wedge block 64 and then inserting the cotter pin 80, guard rail 26 may be rigidly secured against the previously adjusted block mechanism 28—34 and consequently with reference to the main 60 rail 18.

The construction of Fig. 3 differs from that of Fig. 2 only in that inclined bearing faces 82 and 84 are provided in place of the vertical faces shown in Fig. 2, the point of 65 this particular construction being that these faces are at right angles to the supposed line of thrust between the rail 26 and the securing mechanism, such as the rivet 58 and the clip 56 on the plate 10. 70

The construction of Fig. 4 differs from that of Fig. 2 in that the sheared portion of right hand end of plate 10 is, instead of overlapping flange 54^a, corresponding to flange 54, brought up in the overturned end 75 86 which abuts against this flange 54^a, the latter being held in place by the rivet 88 shorter than rivet 58. 86

The constructions of Figs. 5 and 6 differ from that of Figs. 1 and 2 only in that a 80 cast plate 90 having on one end an integral cast clip 92 performing the functions of clip 22 and at the other end an integrally cast bearing block 94, performing the functions of block 42—44 is used in place of the bendable construction. 85

Having thus described my invention, what I claim as new and desire to secure by Letters Patent is:

In mechanism of the class described, a 90 plate adapted to extend under the rails, a bearing block forming a portion of the clamping mechanism rising from the plate, the same comprising a flanged base lying on the plate and an upper portion rising 95 therefrom, means securing the flange portion to the base plate, and a member turned up from the plate beyond the bearing block, and riveted to the bearing block to prevent movement of the bearing block longitudinally of the plate. 100

In witness whereof, I have hereunto subscribed my name in the presence of two witnesses.

BENEDICT T. GIBBS, JR.
